Primary Examiner — George D. Kirschbaum*Assistant Examiner* — Antoinette Martine Suiter(74) *Attorney, Agent, or Firm* — ScienBiziP, P.C.(57) **CLAIM**

The ornamental design for a scribing ruler, as shown and described.

DESCRIPTION

FIG. 1 is a front, right, and top perspective view of a scribing ruler, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a part of a T-shaped intersection; and, FIG. 10 is a partial enlarged view of an area labeled 10 in FIG. 2 comprising a part of a main body.

The dash-dash broken lines shown in the drawings are included for the purpose of illustrating portions of the scribing ruler that form no part of the claimed design.

The dot-dash broken lines shown in the drawings delineate enlarged views and forms no part of the claimed design.
